TOOL FOR MARKING LINOLEUM AND THE
LIKE

Wilbur A. Fanning, Forest Park, Ill.

Application May 14, 1937, Serial No. 142,629

2 Claims. (CL. 33—41)

The present invention has to do with a device for use in connection with providing linoleum or similar material with an inlay strip or ribbon usually of contrasting color.

5 It is ordinarily the practice to score a line by the use of a straight edge as a guide and then by shifting the straight edge to score a companion line at the desired distance therefrom and parallel thereto. Such practice gives rise to inaccuracy in maintaining parallelism. It has been proposed to employ a tool with two scribing points whereby to score both lines at once and thus insure parallelism. It has also been suggested, in order to vary the width of the inlay, 10 that these scribing points be adjustable as to the distance separating them from each other. Even so, as the tool approaches a transverse wall or other obstruction, if the linoleum be in place on a floor, the contact of the tool handle with the obstruction prevents the completion of the 15 lines of scoring, and the lines must be completed as best the operator can, often with resulting misalignment.

My invention goes further than has heretofore 20 been done in providing not only for the adjustment of the scribing points towards and from each other but for the maintenance of uniformity of distance separating the points each from its own side of the mounting frame, thus insuring 25 symmetrical relation whether the tool be operated by pushing or pulling with either side in contact with the guiding straight edge.

In marking linoleum, for instance, as a guide for cutting to receive an inlay ribbon, the distance from the margin having been determined, 30 a long straight edge is employed as a guide for the scoring or cutting tool, the latter being pressed in guiding contact with the straight edge as the tool is drawn along the same with the 35 scoring points in pressure contact with the linoleum. As hereinbefore noted, the direction of operation of the tool cannot be reversed unless the scoring pins, whatever their adjustment as to distance from each other, be maintained equidistant each from its edge of the frame, in which 40 case the direction of travel of the tool can be reversed and either pushed or pulled along the straight edge with the resultant lines of scoring 45 precisely in alignment. Such is the primary purpose of the present invention.

In order that a thorough understanding may 50 be had of the invention and the manner of its use, a preferred embodiment of the same is hereinafter described in connection with the accompanying drawing upon which the description is

predicated. It is to be understood that various changes in the details of construction may be adopted without departure from the essence of the invention, wherefore the description and the drawing are to be taken in an illustrative and not in an unduly limiting sense. 5

In the drawing,

Fig. 1 is a side elevation illustrating a tool embodying the invention;

Fig. 2 is a top plan with a portion broken away 10 to disclose the interior arrangement;

Fig. 3 is a front elevation;

Fig. 4 is a detail of one form of scoring pin partaking of the nature of a knife; and

Fig. 5 is a top plan of a slight modification. 15

Having particular reference to the drawing, there is provided a frame 10 substantially rectangular in shape with guiding sides 11, 12, with a rear side 13, and a front side 14. These sides, instead of being truly rectangular as to outline, 20 may be streamlined or rounded, as indicated in Fig. 1, to permit of slight rocking of the tool whereby to score more or less deeply. The usual operating handle 15 is attached by means of a ferrule 16 to the top of the frame and normally 25 extends substantially in a horizontal direction to the rear of the tool which is thereby usually pushed over the surface of the linoleum 17 or similar material which is to be scored, as indicated at 17a, along straight lines parallel to the 30 guiding straight edge 18.

Within the frame about equidistant between the front and rear thereof is journaled a screw by means of the trunnions 19, which trunnions may be squared, as indicated, for the reception of a turning key or provided with any other convenient means for rotating said screw such as a knurled head. One-half of the screw is provided with a right hand thread as at 20, while the other half as at 21 has a left hand thread. 40 Fixedly mounted within the frame and extending parallel to the screw 20—21 are guide rods 22 and 23. The front side of the frame is open, as indicated at 14a, to accommodate a pair of bars 24 and 25, which bars are threaded respectively 45 upon the screw-halves 20 and 21 equidistant from the center of the frame and equidistant from the two sides 11 and 12. These bars 24 and 25 extend preferably beyond the front side of the frame and are recessed upon their inner opposed faces to 50 receive companion scoring pins 26, 27, the pins being adjustable vertically upon the bars by set screws 28, 29 within vertical slots 30 of the scoring pin. The operative part of the scoring pins may 55 be of any desired configuration, whether conical

for scribing a line to serve as a guide for cutting or having cutting edges, as indicated in Fig. 4, for cutting out a strip of linoleum for the reception of an inlay.

5 In Fig. 4 the scoring pin 31 is shown as having a knife edge 32 both front and rear whereby to effect a cutting action when moved in either direction.

If the tool is used for marking concentric lines 10 a rod of any suitable description may be passed through and secured in holes 33 in the bars 24 and 25 and the tool may be swung in a circle with one end of the rod held at the desired center of curvature.

15 In order to avoid the possibility of a variation in the distances between the parallel scored lines and their distance from the straight edge due to a lateral shifting of the handle 15 towards and from the straight edge 18, the frame 10, instead of having its two sides 11 and 12 contact the straight edge 18, may be provided with bulbous projections 11a and 12a projecting laterally beyond the sides 11 and 12 and transversely aligned with the scoring pins 26 and 27, as shown 20 in Fig. 5, thus minimizing and substantially 25 eliminating any irregularities due to a slight degree of shifting of the handle 15.

From the foregoing description it will be observed that by rotating the screw 20, 21 the bars 30 24, 25 and the scoring pins 26, 27 are adjusted upon the screw and with reference to the frame whereby to vary their distance apart and thus change the width of the strip defined by parallel lines, while at the same time said scoring pins are 35 maintained equidistant each from its own side of the frame. Consequently whether the side 12 of the frame be in guiding contact with the straight edge 18 or the tool be reversed in position so that the edge 11 is in guiding contact with

the straight edge, the lines of scoring will remain at a distance from the straight edge and in perfect alignment with the lines of scoring already impressed upon the material. This enables the tool to be drawn by the operator along the material until a wall or other obstruction be reached and then to be reversed and pushed up to the obstruction, the lines of scoring being in perfect alignment before and after reversal of the direction of operation.

5 I claim:

1. In a device of the character set forth, a frame having sides with forward extensions adapted for guiding contact with a straight edge, a pair of bars slidably guided within the frame, scoring pins mounted on the forward ends of the two bars substantially in line with the frame extensions, means to maintain the bars in parallel relationship, and means to vary the distance separating the pins from each other while maintaining said pins equidistant each from the guiding extension on its own side of the frame.

15 2. In a device of the character set forth, a frame having sides with forward bulbous extensions for guiding contact with a straight edge, a screw journaled transversely within the frame with right and left hand threads at the respective sides of the center, guiding rods mounted on the frame sides on each side of and parallel to the screw, a pair of bars slidably guided on the rods and in threaded engagement with the screw equidistant from the sides of the frame, scoring pins mounted on the ends of the two bars beyond the front of the frame and in alignment with the bulbous extensions, and means to rotate the screw 25 whereby to vary the distance separating the pins from each other while maintaining said pins equidistant each from its own side of the frame.

30 35 WILBUR A. FANNING.
